UNITED STATES PATENT OFFICE

96,538

DESIGN FOR A TEXTILE FABRIC

Curt Erwin Forstmann, Montclair, N. J.

Application November 14, 1934, Serial No. 54,005

Term of patent 14 years

To all whom it may concern:

Be it known that I, Curt Erwin Forstmann, a citizen of the United States, residing at Montclair, in the county of Essex and State of New Jersey, have invented a new, original, and ornamental Design for Textile Fabric, as shown in the accompanying drawing and described in the following specification.

In the drawing, Figure 1 is a plan view of a piece of the textile fabric embodying the design of the present invention;

Figure 2 is a section taken along the line 2—2 of Figure 1.

The fabric depicted is of a single color on which the design motif appears as inclined rows of

contiguous, substantially triangular, nappy plateaus, on a sheared background, the plateaus, on one side, rising without perceptible line of demarcation from the background, on the opposite side, forming a shoulder falling abruptly to the level of the background, adapted to cast a shadow, and on the third side being of progressively increasing elevation above the plane of the background, from the point of mergence of said third side with the first mentioned side, to its point of juncture with the abrupt shoulder.

I claim:

The ornamental design for a textile fabric as shown and described.

CURT ERWIN FORSTMANN.
